UNITED STATES PATENT OFFICE

147,314

DESIGN FOR A MUSIC INFORMATION CHART

Barbara Belle, New York, N. Y.

Application July 31, 1946, Serial No. 132,137

Term of patent 14 years

(CL. D25—1)

To all whom it may concern:

Be it known that I, Barbara Belle, a citizen of the United States, residing in the city of New York, county of Queens, and State of New York, have invented a new, original, and ornamental Design for a Music Information Chart, of which the following is a specification, reference being had to the accompanying drawing, forming part thereof.

Fig. 1 is a plan view of a music information chart, showing my new design, and

Fig. 2 is an edge view thereof.

I claim:

The ornamental design for a music information chart, as shown.

BARBARA BELLE.
